GRINDING WHEEL TRUING APPARATUS

Carl G. Flygare and Charles C. Alvord, Worcester,
Mass., assignors to Norton Company, Worcester,
Mass., a corporation of Massachusetts

Application September 20, 1938, Serial No. 230,832

4 Claims. (Cl. 125—11)

The invention relates to grinding machines, and more particularly to a grinding wheel truing apparatus for truing the operative face of a grinding wheel.

5 One object of the invention is to provide an improved truing apparatus for producing a predetermined operative face on the grinding wheel. A further object of the invention is to provide a truing apparatus for truing the operative face 10 of a grinding wheel for grinding two adjoining surfaces on a work piece, such as a cylindrical surface adjacent to a tapered surface or two adjoining tapered surfaces.

A further object of the invention is to provide 15 a thoroughly practical truing apparatus in which an adjustable forming bar is utilized to true off a corner of the wheel so that the wheel may be accurately formed to grind a cylindrical or tapered face on a work piece and a portion of 20 a tapered surface adjoining the same. A further object of the invention is to provide such an apparatus with a pivotally mounted forming bar having a nut and screw mechanism for adjusting the same. Other objects will be in part obvious or in part pointed out hereinafter.

The invention accordingly consists in the features of construction, combinations of elements, and arrangements of parts, as will be exemplified in the structure to be hereinafter described, and 25 the scope of the application of which will be indicated in the following claims.

In the accompanying drawings, in which is shown one of various possible embodiments of the mechanical features of this invention,

30 Fig. 1 is an end elevation of the improved grinding wheel truing apparatus;

Fig. 2 is a fragmentary plan view of the improved truing apparatus shown in Fig. 1;

Fig. 3 is a rear elevation of the truing apparatus shown in Figs. 1 and 2;

Fig. 4 is a fragmentary plan view showing the forming bar set at an angle for truing a taper adjacent to one edge of the grinding wheel;

Fig. 5 is a diagrammatic plan view showing the arrangement of the wheel and the work when utilized for grinding a cylindrical surface on a work piece adjacent to a tapered surface.

As illustrated in the drawings, a fragment of a grinding machine has been illustrated comprising a transversely movable grinding wheel 10 which is supported on a transversely movable slide (not shown), as is common practice in the grinding machine art. The grinding wheel 10 is partially surrounded by a wheel guard 11. The grinding wheel 10 and its transversely mov-

able supporting slide (not shown) are in turn mounted on a longitudinally reciprocable carriage (not shown) which traverses longitudinally relative to the base of the machine. This machine may be of the type shown in the prior patent to Norton No. 1,096,188 dated May 12, 1914, to which reference may be had for details of disclosure not contained herein.

The work piece 15 to be ground is rotatably supported on a headstock center 16 and a 10 footstock center 17, such as diagrammatically shown in Fig. 5 of the drawings. The footstock center 17 is carried by a footstock 18 which is in turn supported on a pivotally mounted swivel table 19 of the type universally employed on the 15 standard or plain cylindrical grinding machines, such as for example that shown in the expired patent to Norton No. 762,838 dated June 14, 1904, to which reference may be had for details of disclosure not contained herein. The swivel table 19 also serves as a support for a headstock (not shown). A swivel adjustment is provided for adjusting the swivel table so that the axis of the work piece 15 when supported on the centers 16 and 17 is either parallel to or at an angle to the path of travel of the grinding wheel so that either a true cylindrical surface or a tapered surface 20 may be ground.

In grinding a work piece, such as that shown in Fig. 5, which has a cylindrical portion 20 adjoining a tapered surface 21, difficulty has been experienced in grinding the true cylindrical surface up to its junction with the tapered surface and in producing an accurate surface adjacent to the joint therebetween. It has been found that greater accuracy may be obtained if the grinding wheel is formed with a true cylindrical surface 20 for grinding the work piece 15 and is provided with an angled-off portion which is tapered to the same degree as the tapered surface 21 of the work piece 15, so that when the grinding wheel and work piece are traversed longitudinally, as the wheel approaches the end of its stroke toward the right (Fig. 1), the wheel will not only grind the cylindrical surface but the angled-off portion of the wheel will grind a small portion of the taper, thus producing an accurate surface right up to the junction line between the cylindrical and frusto-conical surfaces.

The improved truing apparatus as shown relates particularly to an apparatus for truing a grinding wheel for such an operation. A truing apparatus has been illustrated in the drawings which is attached to the footstock 18. A truing apparatus frame 25 (Fig. 1) is fixedly mounted

on the footstock 18 and is provided with a boss 26 having an aperture 27 which serves as a support for a footstock truing tool 28 having a truing tool diamond 29 mounted in the outer end thereof. A binder or clamping screw 30 serves to lock the truing tool 28 in adjusted position. This well known type of truing tool may be utilized to true a cylindrical portion on the grinding wheel 10 when the grinding wheel and swivel table 19 are traversed or reciprocated longitudinally relative to each other.

The truing apparatus frame 25 has an enlarged head portion 32 which is provided with a central aperture 33. A rod 34 passes through the aperture 33 and is arranged to be clamped rigidly in position therein by clamping screws 35 and 36. The rod 34 serves as a support for a transversely movable truing tool support 37. The support 37 is provided with a vertical downwardly extending arm 38 which is provided with an enlarged boss 39 having an aperture which slidably fits the rod 34. A pair of clamping screws 40 and 41 serve to adjust the boss 39 so that a nice sliding fit may be obtained. The support 37 is provided with a spaced bearing member 42 which is spaced from the boss 39 and which slidably fits on the rod 34. The downwardly extending arm 38 serves as a support for a diamond or truing tool 43 which is preferably located so that the diamond or truing tool 43 contacts with the periphery of the grinding wheel in a horizontal plane passing through the grinding wheel axis and the work axis. A guide bar 45 is rigidly fixed to the downwardly extending arm 38 of the support 37 and is guided by the L-shaped guide block 46 which is fixedly mounted on the frame 25. The guide bar 45 and the guide block 46 serve to guide the frame 37 and prevent any lateral swinging movement thereof during the truing operation.

40 The truing apparatus frame is arranged so that it is normally urged toward the left (Fig. 1) by means of a compression spring 50 which surrounds the rod 34 and is interposed between the bearing boss 42 and an adjustable collar 51 which is secured on the rod 34 by means of a clamping screw 52. A stop collar 53 is provided on the rod 34. The stop collar 53 is provided with a clamping screw 54 and serves to limit the movement of the frame 37 toward the left (Fig. 1).

50 A forming bar is provided for controlling the transverse movement of the frame 37 and the truing tool 43 so as to produce the desired contour on the wheel being trued. As illustrated in the drawings, a straight forming bar 60 is connected by bolts 61 and 62 to a pivotally mounted bracket 63 which is fixedly supported on a vertically arranged shaft 64. The shaft 64 is journaled in spaced bearings 65 and 66 (Fig. 1) in a bracket 67 which is fixedly mounted on the wheel guard 11. An adjusting arm 68 is fixedly mounted on the upper end of the shaft 64 and supports a nut 69 adjacent to its left-hand end (Fig. 2). A rotatable adjusting screw 70 meshes with said nut and is journaled in a bearing 71 fixedly mounted on the bracket 67. The screw 70 is provided with an actuating knob 72 and a graduated dial 73, both of which serve to facilitate adjustment of the position of the forming bar 60.

70 An indicator pointer arm 75 is fixedly mounted on the left-hand end of the arm 68 (Fig. 2) which extends in the path of a graduated scale 76 fixedly mounted on the wheel guard 11. By rotation of the knob 72, the nut and screw mechanism serves to rock the arm 68 and the shaft

64 so as to position the forming bar 60 as desired, that is, either parallel to the relative path of travel between the wheel and work axis or at an angle relative thereto.

8 A bracket 80 which is fixedly mounted to the wheel guard 11 is provided with an elongated slot 81. A clamping screw 82 passes through the elongated slot 81 and is screw threaded into the forming bar 60 and serves to clamp the bar 60 rigidly in adjusted position.

10 A suitable follower 85 is provided for engaging the operative surface of the forming bar 60 to transmit a transverse movement to the diamond or truing tool 43 so as to produce a predetermined shape on the grinding wheel 10. As illustrated in the drawings, the follower 85 is mounted in the outer end of a sleeve 86 which is journaled in a boss 87 formed integral with the truing tool support 37. A rotatable adjusting screw 88 is held against endwise movement by means of an end cap 89 fastened to the end of the boss 87. The screw 88 is screw threaded into the sleeve 86 and serves to facilitate a transverse adjustment of the truing tool support 37 so as to position the truing tool 43 relative to the periphery of the grinding wheel, as desired. The collar 51 is preferably adjusted to compress the spring 50 so that the follower 85 is maintained in engagement with the master or forming bar 60 with sufficient pressure to maintain the diamond or truing tool 43 in position during a truing operation.

15 When the grinding wheel and work piece are reciprocated longitudinally relative to each other in a wheel truing position, the follower 85 following the forming bar 60 will true a predetermined shape on the periphery of the grinding wheel, depending upon the shape of the forming bar 60 and its angular position relative to the path of travel between the wheel and work support. As illustrated in the drawings, a straight forming bar 60 has been provided. This bar, however, may be of any desired shape to produce the desired contour on the periphery of the grinding wheel. As illustrated in Fig. 2, the forming bar 60 has been illustrated as positioned substantially parallel to the path of travel between the wheel and work support, and in which position a true cylindrical surface will be produced on the grinding wheel.

20 The operation of this improved truing apparatus will be readily apparent from the foregoing disclosure. Assuming all of the adjustments have been previously made, in the preferred operation for producing a wheel to grind a work piece such as that illustrated in Fig. 5, in which a grinding wheel having a true cylindrical surface is angled off at one end so as to grind a small portion of the taper 21 adjacent to the cylindrical portion 20 of the work piece 15, it is 25 desirable to utilize the diamond 29 which is held in a fixed position relative to the footstock 18 to true the main portion of the grinding wheel 10 to a cylindrical shape. After this operation has been completed, the forming bar 60 may be 30 adjusted into a position such as that shown in Fig. 4 so that after the cylindrical face has been trued to the desired extent, the corner or edge portion of the grinding wheel may be tapered off so that during the grinding operation, at the end 35 of the relative reciprocatory stroke between the grinding wheel and work, it will engage and grind a small portion of the taper 21, thus enabling the production of an accurate line of division between the true cylindrical surface 20 and the 40

taper 21. After the cylindrical surface 28 has been ground, the swivel table may then be swivelled so that the main portion of the grinding wheel 21 will be in a position to grind the taper 21. In grinding the taper 21, the relative reciprocatory movement between the wheel 10 and the taper 21 will be such that the wheel does not grind up to the junction line between the cylindrical surface and the tapered surface 21 but will merely overlap the small tapered portion ground by the corner portion of the grinding wheel during the grinding of the cylindrical portion 28.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

25 We claim:

1. In a grinding machine having a rotatable grinding wheel, a wheel guard therefor, and a work support including a footstock, said grinding wheel and work support being reciprocable longitudinally relative to each other, a grinding wheel truing apparatus therefor including a supporting frame fixedly mounted on the footstock, a truing tool adjustably mounted on said frame and arranged to true a cylindrical face on the grinding wheel, a transversely movable truing tool carrier on said frame, a second truing tool mounted on said carrier, an adjustable follower on said carrier, and a pivotally mounted forming bar on said guard which cooperates with said follower to produce a transverse movement of the carrier and second truing tool to true a tapered face on the grinding wheel, said truing tools being arranged so that when the grinding wheel and work support are reciprocated longitudinally, the first truing tool trues a cylindrical face and the second truing tool trues a frusto-conical face adjacent to said cylindrical face on the grinding wheel.

2. In a grinding machine having a rotatable grinding wheel, a wheel guard therefor, and a work support including a footstock, said grinding wheel and work support being reciprocable longitudinally relative to each other, a grinding wheel truing apparatus therefor including a supporting frame fixedly mounted on the footstock, a truing tool adjustably mounted on said frame and arranged to true a cylindrical face on the grinding wheel when the grinding wheel and footstock are traversed longitudinally relative to each other, a transversely movable truing tool carrier on said frame, a second truing tool mounted on said carrier, an adjustable follower on said carrier, a forming bar pivotally mounted on said wheel guard which cooperates with said follower to produce a transverse movement of the carrier and

truing tool during the relative longitudinal reciprocation between the grinding wheel and footstock to true a frusto-conical face on the grinding wheel, yieldable means acting upon said carrier to maintain said follower in engagement with the forming bar, and means including a nut and screw mechanism angularly to adjust the position of the forming bar to vary the taper produced upon said wheel.

3. In a grinding machine having a rotatable 10 grinding wheel, a wheel guard therefor, and a work support including a footstock, said grinding wheel and work support being movable longitudinally relative to each other, a grinding wheel truing apparatus including a frame fixedly 15 mounted on said footstock, a horizontally arranged guide bar adjustably supported on said frame, a horizontally movable truing tool carrier supported on said guide bar, a truing tool adjustably mounted thereon, a horizontally adjustable 20 follower on said carrier, a pivotally mounted forming bar cooperating therewith to cause a transverse movement of the carrier and truing tool during the relative longitudinal reciprocation between the grinding wheel and footstock, 25 a vertically arranged shaft on said wheel guard pivotally to support said bar means including a nut and screw adjustment for said follower whereby the position of the follower may be adjusted relative to said carrier precisely to adjust 30 the position of the truing tool relative to the grinding wheel, and means including a nut and screw mechanism rotatably to adjust the vertical shaft so as to precisely position the forming bar 35 angularly to true a tapered face on the grinding wheel.

4. In a grinding machine having a rotatable grinding wheel, a wheel guard therefor, a work support including a footstock, said grinding wheel and work support being movable longitudinally relative to each other, a grinding wheel truing apparatus including a frame fixedly 40 mounted on said footstock, a guide bar adjustably supported on said frame and positioned normal to the axis of the grinding wheel, a movable truing tool carrier supported on said guide bar, a truing tool adjustably mounted thereon, an adjustable follower on said carrier, a pivotally mounted forming bar which is arranged to pivot about an axis normal to the axis of the 50 grinding wheel, said bar having an operative face which may be positioned at an angle relative to the axis of the wheel, said bar cooperating with said follower to cause a transverse movement of the carrier and tool during the longitudinal reciprocation between the grinding wheel and footstock, and means including a nut and screw adjustment for said follower whereby the position of the follower may be precisely adjusted to adjust the position of the truing tool 55 relative to the grinding wheel, and means to adjust the position of the forming bar angularly to true a tapered face on the grinding wheel.

CARL G. FLYGARE.
